EARTH COMPACTOR

Robert S. McKesson, Sierra Madre, Calif.

Application May 26, 1952, Serial No. 289,947

3 Claims. (Cl. 94—50)

My invention relates to machines for use in laying in compacted relationship successive layers or lifts of earth or for use in compacting a mass of earth. In the present construction of highways, airports and the like, it is important that the soil or earth be compressed into dense, compact form. This has led to the utilization of rubber-tired rollers in the nature of trailer vehicles which are drawn over the base material a number of times in order that each layer or lift of the fill or the mass of earth may be compacted into requisite density. There are many special requirements of an earth compactor of this sort and it is a general object of my invention to meet most or all of such requirements.

It is an object of my invention to provide an earth compactor of sturdy, rugged construction suitable for hard use.

Another object of my invention is to provide an earth compactor effective to concentrate a heavy compaction load over a small area of ground in a manner which does not strain the compactor severely.

Another object of the invention is to provide an earth compactor capable of operating under adverse circumstances on terrain of irregular nature.

Another object of my invention is to provide a compactor useful to compact earth adjacent various discontinuities such as walls, curbs, and the like and to compact earth in successive lifts at the same time.

Another object of my invention is to provide an earth compactor readily set or changed in the field to adapt it promptly to variant field conditions.

A still further object of my invention is in general to improve earth compactors.

Other objects, together with the foregoing, are attained in the embodiment of my invention described in the accompanying description and illustrated in the accompanying drawings in which

Figure 1 is a side elevation of an earth compactor constructed in accordance with my invention, a portion of the draft tongue being omitted to reduce the size of the figure.

Figure 2 is a cross section to an enlarged scale of the structure of Figure 1, the plane of section being indicated by the line 2—2 of Figure 1.

Figure 3 is a fragmentary cross section, the plane of section being indicated by the line 3—3 of Figure 2.

Figure 4 is a diagrammatic cross section, similar to Figure 2 but to a reduced scale and showing the earth compactor in one variant form of arrangement for operation.

Figure 5 is a view similar to Figure 4 and showing another variant arrangement of the earth compactor.

Figure 6 is a view similar to Figure 4 but showing a different position of operation of the earth compactor.

Figure 7 is a view comparable to Figure 4 but showing another variant position of operation of the earth compactor.

While my earth compactor can be embodied in a number of different forms and can be varied in many ways, it has successfully been incorporated in the form shown herein. In this form the earth compactor is designed to be drawn over the ground 6 by a tractor or other suitable draft vehicle not shown. The tractor is attached by means of a draft hitch 7 of any suitable sort arranged at the forward end of a draft tongue 8, the direction of advance of the mechanism normally being in the direction of the arrow 9 in Figure 1.

The draft tongue 8 is actually part of a body 11 fabricated of suitable plates and shapes. The body is gen-

erally of a rectangular form, including a front wall 12, a back wall 13, and side walls 14 and 16. Preferably the top of the body is entirely open in order to accommodate ballast and is provided with a marginal reinforcement 17 to stiffen and hold the various body parts. Additionally, the body is reinforced by a surrounding band 19 of suitable structural shapes substantially like channels to assist in supporting relatively heavy ballast within the body. Additionally, a longitudinally disposed vertical web or plate 21 extends from the draft tongue 8 throughout the entire length of the body parallel to the side walls 14 and 16 and at convenient points is reinforced and welded to the general body structure.

Also included in the body is a bottom plate 22 for the most part horizontal and merging with smooth curves at its ends into the forward wall 12 and the rearward wall 13. The sides of the bottom plate join the side walls 14 and 16. Between the forward and rearward walls substantially midway of the body the bottom wall 22 is shaped or formed to provide an arch 23 extending transversely of the earth compactor and defining a partial enclosure 24, that I term a "wheel alley" or "well." Part of the wheel alley is intersected by the web plate 21 for additional stiffness and the lower edge of the web plate is therein reinforced by added angles 26.

In the operation of an earth compactor, it is customary to fill the body with ballast, either sand or some heavy substance such as pig iron or iron ore or concrete or the like. The load of the ballast in the body 11, especially when the earth compactor is made to traverse rough ground, exerts severe strains upon the entire fabricated structure. There is some tendency for the ballast to deform the arch plate 23 which is part of the bottom 22. Part of the deformation so induced is resisted by the spanning web plate 21 and its reinforcements 26.

Additionally as a brace and also to provide part of the ground support for the earth compactor, I provide, as shown in Figures 2 and 3, a pair of longitudinally extending trunnion axles 31 and 32 respectively. These axles are fabricated of a number of metallic shapes and incorporate a pair of parallel longitudinally extending rods 33. The rods are preferably mounted by securing blocks 34 and 36 at their opposite ends. The blocks themselves are fastened to reinforcing channels 37 and 38 included in the bottom 22 of the compactor body. The rods 33 at their opposite ends are reduced in diameter to define shoulders and are so fastened that they are firmly held in or clamped longitudinally between the mounting blocks 34 and 36. Thus, they constitute not only struts spanning the wheel alley 24 but also serve as mountings for the rest of the trunnion axles 31 and 32.

Each of the axles incorporates a pair of bearings 39 and 41 of such shape and size as also to constitute thrust members bearing against the adjacent blocks 34 and 36. The longitudinal position of the trunnion axles is therefore established within close limits. If desired, antifriction thrust bearings can be utilized but in most instances they are not necessary. Each of the trunnion axles 31 and 32 is therefore rotatable about its respective one of a pair of longitudinally extending parallel axes 42 and 43, referred to as "first axes." If desired, the same relative motion can be provided by locking the trunnion axles 31 and 32 to their respective trunnion rods 33 in the mounting blocks 34 and 36. This is primarily a matter of fastening the rods 33 either in the blocks 34 and 36 or in the trunnion axles 31 and 32 as desired.

Mounted on each of the trunnion axles 31 and 32 and in identical relationship so that the description of one applies also to the other is a transversely extending wheel axle 44. The wheel axle is offset by the distance between its rotational axis 46 and the axis 43, for example. The axis 46 extends generally transversely of the vehicle and is the axis of rotation about which the axle 44 is symmetrical. The axis 46 is referred to as a "second axis." The axle 44 is preferably a turned member anchored firmly in the trunnion axle 32 and extends on opposite sides of the center of such trunnion axle.

Mounted for rotation on the oppositely extending portions of the wheel axle 44 are ground engaging wheels

51 and 52 including not only wheel hubs of a suitable nature but also pneumatic tires for supporting the structure. Each of the wheels 51 and 52 is individually journaled so as to be individually rotatable about the second axis 46 and in addition each of the wheels 51 and 52 is of such a size and is so located that it is substantially contained within the wheel alley 24 beneath the arched plate 23 and within the side confines of the plates 14 and 16. The wheels 51 and 52 are also of a size to have adequate clearance with respect to the reinforcing central plate 21. Since the first axis 43 has an offset 53 from the second axis 46 by an amount equal to the shortest distance between such axes, represented by the arrow in Figure 2, there is adequate clearance between one pair of the ground engaging wheels and the adjacent pair of wheels. There is also plenty of clearance between each pair of wheels and the parts of the body despite the fact that the wheels are in effect in eccentric position when they rotate about the longitudinal axes 42 and 43.

This arrangement is particularly valuable under various operating conditions of compaction. Some of these conditions, although by no means all of them, are represented in Figures 2 and 4 to 7. In Figure 2 is disclosed the arrangement of the parts when a relatively low over-all height, low center of gravity and ground clearance are desired, it being observed that the offset 53 extends upwardly from the longitudinal axis 33. In Figure 4 this condition has been changed to afford greater ground clearance by rotating each of the pairs of wheels about its own one of the as illustrated by the arrows 54 and 56 in Figure 2. This rotation is effectuated by jacking up the earth compactor body temporarily and manually rotating the wheels, as shown by the arrows, and then restoring the compactor body. The weight then rests upon the wheels after they have been rotated through substantially one half of a revolution about the first axes. In this higher position, or position of greater ground clearance, as shown in Figure 4, adjacent structures such as a curb 57 are readily cleared by the overhanging parts of the compactor body especially when the compactor is being maneuvered against or away from the curb.

If only one of the pairs of wheels is inverted, as shown particularly in Figure 5, then it is possible simultaneously to compact a lower lift 58 and an upper lift 59 of the terrain. This is especially useful in compacting terraces, shoulders of highway paving, trenches and the like. There is a great advantage in this instance in having the compactor body substantially level since then the center of gravity of the ballast is still substantially central of the ground engaging members.

As illustrated particularly in Figure 6, by utilizing the inversion of one pair of wheels, somewhat as in Figure 5, it is possible to compact an inclined bank, 61, and still keep the center of gravity of the ballast approximately centrally located so that the compactor, even though heavily loaded and even though supported on an incline, is still quite stable.

In Figure 7 there is illustrated a condition substantially the same as that in Figure 2 with relatively small ground clearance or low over-all height but in which the individual pairs of wheels are free to oscillate for initial compaction of irregular terrain.

Since the various wheel positions can readily be arranged in the field merely by lifting the compactor body temporarily, rotating the wheels and then restoring the compactor weight to them, it is possible to adapt the compactor quite quickly to a variety of field conditions. Furthermore, in the event of difficulties such as tire blowouts or the like which sometimes occur, it is possible by removing the blocks 34 and 36 to replace an entire wheel pair unit with a spare unit with very little difficulty.

This can be done by moving the wheels either axially through the wheel alley or dropping them out below the raised body of the compactor. Furthermore, it is possible to utilize tires of different size and different load carrying capacities by making a similar substitution. Furthermore, in the event of blowout of the inside tire, it is possible to move the inside wheel to the outside position by rotating the trunnion axle 180 degrees. It is then possible, when the compactor is equipped with demountable wheels to change any tire without removing the entire trunnion and wheel assembly.

In general, therefore, the earth compactor of my invention represents a substantial advance in the art.

What is claimed is:

15. An earth compactor comprising a body having a transverse well therein, means for confining ballast on said body, a longitudinally extending trunnion axle spanning said well, journals on said body and engaging the ends of said trunnion axle for mounting said trunnion axle on said body for rotation about a first axis, a transversely extending wheel axle, means for securing said wheel axle to said trunnion axle in offset relationship intermediate the ends thereof, ground engaging wheels, means for mounting said ground engaging wheels on said wheel axle on opposite sides of said trunnion axle for rotation about a second axis offset from said first axis, said wheels being disposed in said well and spaced from said body in all positions of said wheels through at least half a revolution of said wheels about said first axis.
20. An earth compactor comprising a body having a transversely extending wheel alley therein, a pair of longitudinally extending trunnion axles spanning said alley, means engaging the ends of said trunnion axles for journaling said axles on said body for rotation about respective ones of a pair of first axes, a pair of transversely extending wheel axles, means for securing each of said wheel axles to a respective one of said trunnion axles in offset relationship intermediate the ends thereof, ground engaging wheels, means for mounting said ground engaging 25. wheels on said wheel axles in pairs one on each side of said trunnion axles for rotation about second axes offset from said first axes, said wheels being disposed in said alley and spaced from said body and from each other in all positions of said wheels through at least a half revolution of said wheels about said first axes.
25. An earth compactor comprising a body having a transversely extending wheel alley therein, a pair of longitudinally extending trunnion axles spanning said alley, means engaging the ends of said trunnion axles for journaling said axles on said body for rotation about respective ones of a pair of first axes, a pair of transversely extending wheel axles, means for securing each of said wheel axles to a respective one of said trunnion axles in offset relationship intermediate the ends thereof, ground engaging wheels, means for mounting said ground engaging 30. wheels on said wheel axles in pairs one on each side of said trunnion axles for rotation about second axes offset from said first axes, said wheels being disposed in said alley and spaced from said body and from each other in all positions of said wheels through at least a half revolution of said wheels about said first axes.
30. An earth compactor comprising a body having a transversely extending wheel alley therein, a pair of longitudinally extending trunnion axles spanning said alley, means engaging the ends of said trunnion axles for journaling said axles on said body for rotation about respective ones of a pair of first axes, a pair of transversely extending wheel axles, means for securing each of said wheel axles to a respective one of said trunnion axles in offset relationship intermediate the ends thereof, ground engaging wheels, means for mounting said ground engaging 35. wheels on said wheel axles in pairs one on each side of said trunnion axles for rotation about second axes offset from said first axes, said wheels being disposed in said alley and spaced from said body and from each other in all positions of said wheels through at least a half revolution of said wheels about said first axes.
35. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
40. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
45. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
50. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
55. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
60. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
65. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
70. An earth compactor comprising a body including a bottom in part formed as a transversely extending arch of predetermined radius open toward the ground and at both ends to define a wheel alley, a pair of longitudinally extending horizontal trunnion axles spanning said alley, means for journaling the opposite ends of said trunnion axles on said body at points a predetermined transverse distance apart, a pair of transversely extending wheel axles each joined adjacent its center to the central portion of an associated one of said trunnion axles in an offset relationship, and ground engaging wheels rotatably mounted on said wheel axles on opposite sides of said trunnion axles, each of said wheels having a radius from the associated one of said trunnion axles less than the distance to said wheel alley and less than half said predetermined distance between said trunnion axles.
